UNITED STATES PATENT OFFICE.

EDWARD A. STAFFLIN, OF TOLEDO, OHIO.

PHOTOGRAPHIC-PRINTING APPARATUS.

1,084,046.

Specification of Letters Patent. Patented Jan. 13, 1914.

Application filed May 26, 1913. Serial No. 769,869.

To all whom it may concern:

Be it known that I, EDWARD A. STAFFLIN, a citizen of the United States, and a resident of Toledo, in the county of Lucas and State of Ohio, have invented a certain new and useful Photographic-Printing Apparatus; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to photography, and particularly to printing apparatus for use in connection therewith; and has for its object the provision of a simple and inexpensive apparatus of this character, which is capable of use in connection with either artificial or sun light, is easily operable to effect a rapid and efficient printing of photographs, and is capable of transmitting a bright or subdued light to the parts in which the printing takes place, thus materially enhancing the practicability and commercial value thereof.

Further objects and advantages of my invention will be apparent from the following detailed description of the same.

The invention is fully described in the following specification, and while, in its broader aspect, it is capable of embodiment in numerous forms, a preferred embodiment thereof is illustrated in the accompanying drawings, in which—

Figure 1 is a central vertical section of an apparatus embodying the invention. Fig. 2 is a front elevation thereof. Figs. 3 and 4 are enlarged sections of two of the slide frames, and Fig. 5 is a perspective view of the several frames in spaced assembled relation.

Referring to the drawings, 1 designates a wall of a room, having an opening or window 2 therein through which day light or an artificial light may be directed from one side to the other of the portion. The light is preferably subdued or mellowed in its passage through the window by the provision of a white tissue sheet 3 or other suitable light subduing means therein, the tissue in the present instance being carried by a sash or frame 4.

A cabinet or printing apparatus is attached to the inner side of the wall 1 around

the window 2 to separate such window from the room in which the operator works, and comprises, in the present instance, a wall or side 5, which preferably inclines upward and inward from the wall 1 at the lower edge of the opening 2, and has opposite ends 6. Declining from the wall 1 at the upper edge of the opening 2 to the upper edge of the side 5 is a frame 7, which is preferably mounted for longitudinal sliding movements in suitable slide-ways 8 in the wall 2 and side 5 to permit it to be removed from the apparatus when desired. This frame is provided with three panels or openings lengthwise thereof, the center of which is left open, as shown at 7^a, while the end panels are closed by a light subduing or interrupting material, such, for instance, as ruby colored paper 7^b.

A slide frame 9 of similar construction to the frame 7 is mounted immediately above the frame 7 for longitudinal sliding movements in the ways 8, and has its center panel open, as at 10, and its end panels closed by ruby colored paper or other suitable light subduing or interrupting material 11. The center opening 10 of this frame may be restricted at will by the provision of an opaque plate 12, which is carried by the frame for sliding movements longitudinally thereof over such opening. A handle 13 projects from the front or lower edge of the frame 9 through a registering longitudinally-disposed slot 14 in the upper portion of the side 5 to facilitate a movement of the slide frame, the length of the slot being equal to the desired length of movement of the frame.

A printing frame 15 is stationarily mounted over the opening 7^a of the frame 7 immediately above the slide frame 9, and is of suitable size to entirely cover said opening. A printing opening 16 of suitable size is provided in the frame 15 and is surrounded in spaced relation thereto on the outer side of the frame by a flange or shoulder 17 for holding a negative and print in proper relation to the opening, as is apparent. A cover 18 is hinged to the upper portion of the shoulder 17 at the upper side of the opening 16 for fitting down into the negative or plate-receiving portion of the printing frame, and is shown as having a weighted cord 19 attached to its free edge and passing over an elevated sheave 20 for normally holding the cover in open position. A negative plate 21 is shown in Fig. 1 as being

mounted within the printing frame over the opening 16 therein. The frame 15 is removably held to the upper side of the printing cabinet by pivoted catch members 22, or 5 in any other suitable manner, to enable frames having openings 16 of different sizes to be placed in printing position.

Mounted for sliding movements in a portion of the slide-ways 8 immediately below 10 the frame 7 is a sash or slide-frame 23 corresponding in shape and size to the opening 7^a of the frame 7, and having its opening closed by a light colored light subduing or mellowing diaphragm 24, such, for instance, 15 as white tissue. This frame is placed in register with the opening 7^a of the frame 7 when it is desired to subdue the printing rays passing through such opening and to effect a slower printing than would be the 20 case if the light rays from the interior of the cabinet to the opening 16 of the printing frame were not obstructed.

A box 25 for carrying the sensitive printing sheets 26 is preferably disposed below 25 the inclined side 5, being secured to the wall 1 by a bracket, or in any other suitable manner, and is provided with a cover 27 for excluding light from the interior thereof when the cover is closed. The side 5 is provided 30 with an opening, which is closed at the outer side thereof by a sheet of light subduing material 28, such, for instance, as ruby paper; so that the box 25 will be subjected to a light of a sufficiently subdued nature to 35 prevent injury to the printing sheets 26 when subjected thereto. The inner portion of the opening in the side 5 is covered by a white sheet of tissue 29, or any other suitable material, which tends to reflect the light 40 rays upward within the cabinet.

In the use of my printing apparatus day light or an artificial light is permitted to enter the cabinet through the window 2 in the wall 1, and such light, which is preferably 45 partially subdued or mellowed by passing through a white sheet of tissue 3, is then reflected through the opening 7^a of the stationary frame 7 and against light interrupting material 11 in the end panel of the frame 9, which is in register with the opening 7^a, thus preventing the passage of printing rays of light to the opening 16 of the printing frame 15. The operator, having placed a negative plate or film and a sheet 50 26 to be printed over the opening 16 of the printing frame, lowers the cover 18 to its closed position and then moves the slide frame 9 lengthwise in its slide-way until the opposite end panel thereof is moved into 55 register with the printing parts. As the frame 9 is moved in this manner the light rays from within the cabinet pass through the center opening 10 of the frame 9 and effect a printing of the paper within the 60 printing frame. The operator then releases

the cover 18, which raises under the action of the weighted cord 19, and, after taking out the printed sheet and putting in a fresh sheet 26, again lowers the cover 18 over the same and moves the frame 9 back to its previous position to effect the printing of another sheet. Should it be desired to reduce the size of the opening 10 in the frame 9 so as to shorten the period of exposure upon a quick passing of such opening under 70 the printing frame opening the opaque plate 12 may be properly adjusted in the frame 9 for such purpose. The light subduing frame 23 may also be moved in register with the opening 7^a of the frame 7 to cause a mellowing of the printing rays. 80

The purpose of providing the openings in the end panels of the two frames 7 and 9 with a semi-transparent material, such, for instance, as ruby paper, is to permit sufficient light rays to enter the operating room from the interior of the cabinet to facilitate the work of the operator without injury to the sensitive printing paper which it is necessary for him to handle, otherwise the 90 end panels of the frames 7 and 9 might be made of opaque material. 95

It is evident that by the use of an apparatus of this character prints may be made as rapidly as the slide frame 9 can be moved from one end to the other of its working movements and the prints removed from the printing frame and fresh print paper substituted therefor. It is also evident that the period of exposure can be easily and quickly regulated to a nicety and that the light rays may be subdued as the nature of the print or the brightness of the printing rays may require. 100

I wish it understood that my invention is 105 not limited to any specific construction or arrangement of the parts except in so far as such limitations are specified in the claims.

Having thus described my invention, what I claim as new, and desire to secure by Let- 110 ters Patent, is,—

1. In a printing apparatus of the class described, a light cabinet, a printing frame having an opening in communication with said cabinet, and a movable member having 115 an open portion and light interrupting portions at opposite sides of its open portion, the open portion of said member being adapted to open communication between said printing frame opening and the interior of the cabinet when said movable member is moved to place one or the other of the light interrupting portions thereof in register with the printing frame opening. 120

2. In a printing apparatus of the class de- 125 scribed, a cabinet, a printing frame having an opening in communication with the interior of said cabinet and a frame slidable between said printing frame and the interior of the cabinet and having an opening 130

- therein adapted to register with said printing frame opening during a predetermined portion of the shifting movements of said slide frame and having light interrupting portions at opposite sides of its opening which alternately register with and interrupt the light rays to the printing frame opening as the slide frame is shifted in first one and then the other direction.
5. In a printing apparatus of the class described, a light cabinet, a printing frame mounted on said cabinet and having an opening in communication with the interior thereof, a slide frame having alternately disposed open and light interrupting portions and being movable between said printing opening and the interior of the cabinet to alternately place said open and light interrupting portions in register with the printing frame opening, and means carried 20 by said slide frame for regulating the size of the open portion thereof.
6. In a printing apparatus of the class described, a light cabinet having an opening 25 in a wall thereof, a printing frame disposed without said opening, a slide member having an open portion movable past said opening, said member being operable to alternately open and interrupt the communication 30 between said opening and frame, and means slidable with relation to the slide frame and movable into or out of register with said opening for mellowing the light rays passing therethrough.
35. In an apparatus of the class described, a light cabinet having an opening in a wall thereof, a printing frame removably mounted without said opening in register therewith, a slide member operable to alternately open and interrupt the communication 40 between said opening and frame, and means carried by said member for changing the period of exposure which occurs when the member is moved from one position to another.
45. In an apparatus of the class described, a cabinet having an opening in a wall thereof, a printing frame mounted without said opening in register therewith, a member 50 slidable between said opening and frame and operable to alternately open and interrupt the communication between said frame and the interior of the cabinet through said opening, means carried by said member for changing the period of exposure which occurs when the member is moved from one 55 position to another, and light subduing means at the inner side of and movable into or out of register with said opening.
60. In an apparatus of the class described, a cabinet having an opening in a wall thereof and a semi-transparent portion at one side of said opening, a printing frame disposed without said opening in register therewith, and a movable member having an 65 open portion and light interrupting portions alternately movable into register with said opening by movements of said member, the open portion of said member being adapted to stand in register with said semi-transparent wall portion when said light interrupting portion is in register with said opening.
70. In an apparatus of the class described, a cabinet having an opening in a wall thereof and having semi-transparent portions at opposite sides of said opening, a printing frame mounted without the opening and in register therewith, and a slide member movable at the inner side of said printing frame and having light interrupting portions and an interposed open portion, said open portion being movable with the slide member past the wall opening to open communication between said frame and the interior of the cabinet and standing in register with one of said semi-transparent portions when either one of the light interrupting portions of the member is in register with said frame and opening.
75. In an apparatus of the class described, a cabinet having an open side provided with opposing slide-ways, two frames disposed one without the other and slidable in said ways and each having a centrally disposed open portion and light interrupting end portions, one frame remaining stationary during an operation of the apparatus and the other frame being movable relative thereto to pass its open portion by the open portion of the stationary frame and to place one or the other of its light interrupting end portions in register with the open portion of said stationary frame, and a printing frame disposed without said slide frame in register with the open portion of the stationary frame.
80. In an apparatus of the class described, a cabinet having an open side provided with opposing slide ways, two frames disposed one without the other and slidable in said ways and each having a centrally disposed open portion and light interrupting end portions, one frame remaining stationary during an operation of the apparatus and the other frame being movable relative thereto to pass its open portion by the open portion of the stationary frame and to place one or the other of its light interrupting end portions in register with the open portion of said stationary frame, a printing frame disposed without said slide frame in register with the open end portion of the stationary frame.
85. In an apparatus of the class described, a cabinet having an open side provided with opposing slide ways, two frames disposed one without the other and slidable in said ways and each having a centrally disposed open portion and light interrupting end portions, one frame remaining stationary during an operation of the apparatus and the other frame being movable relative thereto to pass its open portion by the open portion of the stationary frame and to place one or the other of its light interrupting end portions in register with the open portion of said stationary frame, a printing frame disposed without said slide frame in register with the open end portion of the stationary frame.
90. In an apparatus of the class described, a cabinet having an open side provided with opposing slide ways, two frames disposed one without the other and slidable in said ways and each having a centrally disposed open portion and light interrupting end portions, one frame remaining stationary during an operation of the apparatus and the other frame being movable relative thereto to pass its open portion by the open portion of the stationary frame and to place one or the other of its light interrupting end portions in register with the open portion of said stationary frame, a printing frame disposed without said slide frame in register with the open end portion of the stationary frame.
95. In an apparatus of the class described, a cabinet having an open side provided with opposing slide ways, two frames disposed one without the other and slidable in said ways and each having a centrally disposed open portion and light interrupting end portions, one frame remaining stationary during an operation of the apparatus and the other frame being movable relative thereto to pass its open portion by the open portion of the stationary frame and to place one or the other of its light interrupting end portions in register with the open portion of said stationary frame, a printing frame disposed without said slide frame in register with the open end portion of the stationary frame.
100. In an apparatus of the class described, a cabinet having an open side provided with opposing slide ways, two frames disposed one without the other and slidable in said ways and each having a centrally disposed open portion and light interrupting end portions, one frame remaining stationary during an operation of the apparatus and the other frame being movable relative thereto to pass its open portion by the open portion of the stationary frame and to place one or the other of its light interrupting end portions in register with the open portion of said stationary frame, a printing frame disposed without said slide frame in register with the open end portion of the stationary frame.

without said opening in register therewith, and a slide member having end portions of a light interrupting nature and an intermediate open portion, said member being movable to successively move said portions into register with the wall opening in the cabinet with which said printing frame registers.

In testimony whereof, I have hereunto signed my name to this specification in the presence of two subscribing witnesses.
